C. W. McCOY,
APPARATUS AND PROCESS FOR COOLING VEHICLES,
APPLICATION FILED OCT. 30, 1916.

1,342,123.

Patented June 1, 1920.

UNITED STATES PATENT OFFICE.

CHARLES W. MCCOY, OF SPRAGUE, WASHINGTON.

APPARATUS AND PROCESS FOR COOLING VEHICLES.

1,342,123.

Specification of Letters Patent.

Patented June 1, 1920.

Application filed October 30, 1916. Serial No. 128,613.

To all whom it may concern:

Be it known that I, CHARLES W. MCCOY, a citizen of the United States, residing at Sprague, in the county of Lincoln and State 5 of Washington, have invented a certain new and useful Improvement in Apparatus and Processes for Cooling Vehicles, of which the following is a specification.

This invention relates to a process and apparatus for cooling apartments, and has for its object to provide a new and improved process and apparatus for this purpose. The invention is particularly adapted to be used in connection with refrigerator 10 cars or vehicles, or vessels, that is, with moving apartments. In the use of refrigerator cars it is exceedingly desirable and important to secure a substantially uniform temperature throughout the interior of the 15 car. With the present refrigerating cars this cannot be done, as the circulation produced is unnatural and non-uniform. By means of the present device, a natural and substantially uniform circulation is secured 20 and hence a substantially uniform temperature is provided throughout the car. In the present device I have also illustrated apparatus by means of which the movement of the car or other vehicle is utilized to circulate the 25 cooling agent. In the refrigerating apparatus now used on cars, tanks are placed at the ends of the cars, said tanks containing ice and salt. When the ice melts under these 30 conditions a temperature is produced at the ends of the car, which is entirely too low, being under certain conditions in the neighborhood of zero Fahrenheit. This low temperature either destroys or injures the perishable material near the tanks and there 35 must be provided some protective means against this injury, such as an interposed gate or barrier of some kind. In these systems, the temperature near the middle of the car is not low enough, and hence the perishable material near the middle of the 40 car is not cooled sufficiently and is liable to be injured because of the higher temperature.

One of the objects of this invention is to 45 provide a process and apparatus for regulating the temperature of apartments wherein there is a reserve of temperature

varying material which is rendered inoperative so far as varying the temperature of apartments is concerned while it is held in 5 reserve, and then withdrawing from this reserve as required to maintain the temperature of the apartment substantially at the temperature desired as by insulating the receptacle in which the reserve temperature 6 varying material is contained and then passing it through an insulated pipe or pipes so that it acts while in this pipe or pipes to regulate the temperature of the apartment.

This invention also has for its object to 61 economize the consumption of ice or other cooling agent and greatly increasing the efficiency thereof. This system also permits the cars to be made of greater length, still 66 have the temperature properly equalized, 71 thereby producing a further possibility of increase of efficiency and reduction of cost in the transportation of perishable food-stuffs. The invention is particularly adapted for use in refrigerating apparatus to be 76 used to preserve perishable freights in transportation from one point to another.

The invention is illustrated in the accompanying drawings, wherein.

Figure 1 is a view of an apparatus particularly adapted to be used in refrigerating 80 cars;

Fig. 2 is a diagrammatic view showing the circulatory system;

Fig. 3 is a sectional view taken on line 85 3—3 of Fig. 2;

Fig. 4 is a diagrammatic view showing the circulation of the air;

Fig. 5 is a sectional view of a modification.

Like numerals refer to like parts throughout the several figures.

Referring now to the drawings, I have shown a plurality of tanks 1, 2, 3 and 4. The tanks 1 and 2 are located near one end 95 of the car and the tanks 3 and 4 near the other end of the car. In the particular construction shown, the tanks 1 and 2 are made in a single structure divided by a partition 5 so as to form two tanks. The tanks 3 and 10 4 are made in the same manner and divided by a partition 6. The partitions 5 and 6 are provided with one or more valves 7, which are adapted to open in one direction only,

and which are opened in this direction by the pressure of the liquid on one side thereof, and closed by the pressure of the liquid on the other side thereof, thus preventing a backward flow of the liquid. These valves may be formed in any desired manner, and as herein shown, consist of pieces of material the proper size to close the opening controlled thereby, and hinged at 8 so as to move freely in one direction under the pressure of the liquid to uncover the opening and permit the flow of liquid therethrough, but to close so as to prevent backward flow of the liquid. I also prefer to provide on each side of the partitions 5 and 6 the screens 9. These screens prevent the ice, when ice is used in the tanks, from obstructing or injuring the valves, but permit the free flow of the liquid. The tanks 2 and 3 are connected together by a pipe 10, while the tanks 1 and 4 are connected together by a pipe 11. The valves 7 are arranged so that the liquid must always flow in the same direction through the system, the apparatus forming as it were, a complete circulatory system. When the vehicle is moving, it is rocking from side to side and from end to end, and this rocking motion produces a variation in the pressure of the liquid in different parts of the system responsive to the movement of the tanks, thereby causing an automatic circulation of the liquid through the system in a pre-determined direction responsive to the variations in pressure utilizing the lowered pressure in that part of the system from which the moved liquid came and the increased pressure in that part of the system in which the moved liquid is received to produce this forward movement of the liquid in the system to equalize the pressures.

Referring now to Fig. 2, if for example, the car rocks so that tanks 2 and 3 are lowered and tanks 1 and 4 raised, liquid will pass from tank 1 into tank 2 through the valve 7. The valves between tanks 3 and 4 are oppositely placed to those between tanks 1 and 2 so that the liquid cannot pass from tank 4 to tank 3 but can pass from tank 3 to tank 4. There will therefore be no liquid passing from tank 4 to tank 3 under the conditions just mentioned. If, now, the car tips in the other direction to lower tanks 1 and 4 and raise tanks 2 and 3, the valves 7 between tanks 1 and 2 are closed and the valves between tanks 2 and 3 and 4 open to permit liquid to pass from tank 3 to tank 4. Liquid will also pass from tank 2 to tank 3 due to the increased level or pressure in tank 2. Liquid will also pass from tank 1 to tank 4 to replace the liquid previously discharged therefrom. If, now, the car rocks back in the other direction, liquid will pass from tank 4 to tank 1, but the

valves 7 will prevent its passage from tank 4 to tank 3. It will thus be seen that this operation will be repeated and a forward circulation of the liquid secured by the movement of the car as it travels along the track. It will further be seen that this movement is a waste movement and that it is this waste movement which causes the circulation.

I prefer to insulate tanks 1, 2, 3 and 4 on the bottom and the sides by some heat insulating material 12, although the bottom of the tanks or a portion thereof may be without insulation as at 12^a, Fig. 5, if desirable for securing a uniform temperature in the car. The pipes 10 and 11 are comparatively large and are of sufficient diameter to secure the proper cooling effect at the center of the car and the proper uniformity of temperature. By making these pipes of the proper size there is also provided a circulation when the car is standing still, due to differences in temperature. This circulation is brought about by the fact that since the tanks are insulated and the material 12 therein is not used for temperature varying purposes there is provided a reserve of this temperature varying material, and as the material in the pipes becomes changed in temperature the warmer material goes to the top of the pipes and flows therewith, while the colder material goes to the bottom, and thus a certain amount of circulation is secured. I may use any desired cooling solution or liquid. I may, for example, place ice and salt in the tanks, the melting of the ice producing a cold brine which circulates through the system. Or, I may simply insert a cold liquid into the tanks, such liquid being cooled to the desired temperature at different points along the road, by any desired cooling apparatus, and injected into the tanks at these points as the cars travel along the road. It will be seen that by properly insulating the tanks, the cooling effect is practically limited to the pipes 10, 11 and 11, which extend substantially the length of the car or the apartment to be treated. Under these conditions the air at the top of the car all along the car will be cooled by these pipes, that is, lowered in temperature, and under the natural law of circulation this cooled air will drop to the bottom of the car and at the same time the warmer air in the car will rise to the top thereof as indicated diagrammatically in Fig. 4, and this warmer air coming into contact with the pipes 10 and 11 will be lowered in temperature, while the colder air which drops to the bottom of the car will under natural conditions be raised in temperature, the cooled warm air again dropping and the warmed cool air again rising, thus producing a natural uniform circula-

tion throughout the car and hence a substantially uniform temperature throughout the car.

I have described in detail a particular construction embodying the invention, but it is of course evident that the parts may be varied in many particulars, and I therefore do not limit myself to the particular construction shown.

10 It will be noted in the use of temperature-varying devices where the temperature is regulated through a comparatively long period, it is necessary to have more temperature-varying material or fluid than is required to be used at any given time, and this excess or surplus material is one of the causes of the trouble and defectiveness of such devices, for when this surplus or excess portion of the temperature-varying material 20 is unprotected so that it acts while in the receptacle in which it is contained so that the receptacle with this excess material therein, acts to vary or assist in varying the temperature, it will be seen that certain evil 25 results are produced, namely, that the temperature is varied to too great a degree, and is brought lower than is required because more material is used at a given time than is required to produce the desired temperature 30 and also that the temperature-varying effectiveness is used up too rapidly. Now it will be noted that by means of this process and apparatus I overcome these difficulties, for instead of having a surplus or 35 excess of material which is acting substantially at all times, I provide a reserve, that is, I provide a quantity of temperature-controlling material and protect it so that it is not acting, and I draw from this reserve as required to secure the desired temperature. This reserve is secured by providing storage places in which the reserve may be kept and protected by suitable insulation, the arrangement being such that 40 at any given time, only such portion of the material is in effect used, or in use, as is required to secure the proper temperature at the particular time of use, the storage receptacle or receptacles being drawn upon 45 as required to maintain the proper temperature. By this means I am enabled to prevent temperatures that are too low and also prevent undue variation of temperature, and I am also able to reserve or store up the 50 temperature-varying power so as to maintain it for a very considerable length of time, thus not only securing greatly improved results but very greatly increase the efficiency of the device.

0 I claim:

1. An apparatus for regulating the temperature of apartments comprising separated receptacles for receiving the temperature varying material, the exposed surfaces

of said receptacles being insulated by heat 65 insulating materials, uninsulated pipes connecting with said separated receptacles and means for causing the temperature varying material from said receptacles to flow through said pipes, the temperature varying 70 effect of the apparatus being substantially confined to the temperature varying material in the uninsulated pipes.

2. An apparatus for regulating the temperature of an apartment comprising a receptacle to receive ice and salt and the brine from the melting thereof and located in said apartment the temperature of which is to be regulated, means for rendering the temperature varying material inoperative in 75 regulating the temperature of said apartment, while it is in said receptacle, an uninsulated pipe or pipes connected with said receptacle and through which the brine due to the melting of the ice and salt is circulated, the cooling effect of the apparatus being substantially confined to the liquid brine in the uninsulated pipe or pipes. 85

3. A device for regulating the temperature of vehicles comprising a tank at each end of the vehicle, a partition extending across each tank, a valve in each partition, the valve in one partition opening in one direction and the valve in the other partition opening in the opposite direction, pipes 90 connecting the sections of said tank on opposite sides of said partitions, and guards 95 on opposite sides of each partition for protecting said valves.

4. The process of regulating the temperature of an apartment which consists in providing a reserve of salt, ice, and brine located in the apartment, the temperature of which is to be regulated, and rendering this reserve substantially inoperative so far as 100 regulating the temperature of the apartment is concerned, while it is held in reserve, and then withdrawing cold brine from the reserve and utilizing this cold brine in liquid form to maintain the temperature of 105 the apartment substantially at the temperature required. 110

5. The process of regulating the temperature of an apartment which consists in providing separated sources of supply of cold 115 brine near the top of the apartment and at opposite ends thereof, rendering said brine substantially inoperative in regulating the temperatures of the apartment while confined to said sources of supply, and circulating the brine back and forth between the sources of supply and confining the cooling 120 effect on said apartment to the brine while circulating between said sources of supply.

6. The process of regulating the temperature in an apartment which consists in providing a reserve of temperature varying material located in said apartment, the tem- 125

perature of which is to be regulated, and rendering this reserve of temperature varying material inoperative so far as varying the temperature of the apartment is concerned while it is held in reserve, and then withdrawing from this reserve as required, and circulating said withdrawn temperature varying material through a portion of said apartment to maintain the temperature of the apartment substantially at the temperature desired, and returning the temperature

varying material to said reserve after it has been utilized in assisting to maintain the apartment at the temperature desired.

In testimony whereof, I affix my signature 15 in the presence of two witnesses this sixth day of September, 1916.

CHARLES W. McCOY.
